UNITED STATES PATENT OFFICE.

WILLIAM H. HOLLOPETER, OF PORTLAND, OREGON.

INTERNAL-COMBUSTION ENGINE.

No. 828,584.

Specification of Letters Patent. Patented June 29, 1909.

Application filed July 16, 1907. Serial No. 383,994.

To all whom it may concern:

Be it known that I, WILLIAM H. HOLLOPETER, a citizen of the United States, residing at Portland, in the county of Multnomah 5 and State of Oregon, have invented a new and useful Internal-Combustion Engine, of which the following is a specification.

This invention relates to an explosion or internal combustion engine of the four cycle 10 type, which is designed to give a variable speed to the driving shaft with constant power.

One object of this invention is to provide a mechanism by means of which the speed of a 15 shaft driven by an internal combustion engine may be gradually changed from an extremely slow to an extremely rapid rotation, or the reverse, without the use of changeable speed gearing.

20 With this and other objects in view the invention consists of the novel construction, combination and arrangement of parts hereinafter described and pointed out in the several claims.

25 In the accompanying drawings:—Figure 1 is an elevation of a portion of a multi-cylinder internal combustion engine, three cylinders only being shown operating to revolve the same crank shaft, one cylinder and part 30 of the frame being in section. Fig. 2 is a transverse sectional view on the line 2—2 of Fig. 1. Fig. 3 is an end elevation, partly in section of the frame, a portion of a cylinder, and the speed changing mechanism.

35 Similar numerals of reference indicate the same parts on all the figures.

The numeral 1 indicates part of the skeleton frame of a multi-cylinder explosion or internal combustion engine, comprising two 40 similar vertically placed side supports 2 (one only being shown in the drawing), suitably spaced apart and firmly connected together in any well known manner. Extending from one side support to the other and at corresponding ends thereof, is a flat base plate 3 secured to each side support on the top.

Bolted to the base plate 3 is an explosion cylinder 5, or, as represented in the drawings, a plurality of such cylinders. The cylinders 5 are common to this type of engine and need not be described further than to say that they are open at their inner ends, provided with means for cooling, and at their outer ends are to be found inlet and exhaust valves, and in each cylinder an explosion chamber. Within each cylinder is a recipro-

cating piston 6 operating through a pitman 7, a rocking lever 8 fulcrumed on a shiftable shaft 9. The opposite end of the rocking lever 8 rotates the driving shaft 10 by means 30 of a link 11, pivoted thereto, engaging a crank 12 on said shaft. The shiftable fulcrum shaft 9 is preferably tubular and projects through an inclined slot 13 in each side support 2, one end of said shaft having secured thereto a worm wheel 14 rotatable by a worm 15 on one end of a telescopic shaft 16, said shaft end being carried by a bearing 17 hung on the fulcrum shaft 9 as clearly shown in Figs. 1 and 3. Each end of the fulcrum 70 shaft turns in a sliding bearing 18 situated between upper and lower guide bars 19—20 integral with or attached to the inner face of each side support 2 on opposite sides of the inclined slot 13. On the inner edge of each 75 guide bar 19 is a rack 21 with which a pinion 22, secured to the fulcrum shaft 9, engages. When therefore, the worm 15 is rotated, the fulcrum shaft turns and at the same time, through the pinion and rack above described, it moves bodily in the slots 13 toward or from the main or crank shaft 10, the direction of movement depending upon the direction in which the worm is rotated. The slots 13 are inclined downwardly from the cylinder to 80 ward the crank shaft at a certain predetermined angle for a purpose to be described later on.

Each rocking lever 8 is provided with a long longitudinal slot 23 in which a sliding bearing box 24, carried by the fulcrum shaft 9, is arranged to slide as said shaft is moved. A rack 25 is fixed on one side of each rocking lever 8 above the longitudinal slot, with which a pinion 26, secured on the fulcrum 95 shaft 9, engages. The object of the rack and pinion is to keep the rocking lever from moving endwise as the fulcrum shaft 9 travels along the slot 23 to change the leverage; also, to prevent the rocking lever from becoming 100 displaced while the engine is running which would happen were not some means employed for locking said lever to the fulcrum shaft, as for instance, by the teeth of the pinion 26 and rack bar 25.

105 With the fulcrum shaft 9 in the position shown in the drawings, the length of piston stroke will be the same as the crank throw, but, as the fulcrum shaft 9 is carried in the direction of the cylinder 5 the length of piston stroke becomes shorter, while if the fulcrum shaft be moved in the opposite direc- 110

tion or toward the crank shaft the piston stroke becomes longer, it being understood that the crank throw is a constant quantity. The guides in the frame along which the fulcrum travels are inclined at such an angle to the length of the rock arms when the latter are in the median position, that the ratio between the piston displacement and the clearance volume remains constant for any length of stroke. Hence the explosive mixture being compressed to the same degree and the exploded gases having the same expansive ratio, the pressure on the piston at any part of its stroke is the same for all strokes, and if the resistance to the piston movement does not vary, the piston speed will remain constant for all strokes, and, since the number of strokes and the speed of the crank vary inversely as the length of stroke when maintaining the same linear speed, it is obvious that the piston speed may remain constant and develop the same power for any speed of crank.

The skeleton frame 1 is preferably covered by a sheet metal casing 71 to protect and inclose the rock levers, cranks and connecting parts.

The means for rotating the worm shaft will depend upon the use to which the engine is put. One form of operating mechanism is illustrated in Fig. 3 where it will be seen that the shaft 16 is made in two parts, a lower or socketed section 27 carrying the worm 15 and seated at one end in the bearing 17 and at the other end in a second bearing 28 attached to the side support 2, and a squared upper section 29 longitudinally movable within the socketed member and provided with a bevel gear 30, at its upper end engaging a larger gear 31 provided with any convenient means for rotating it.

The pistons are lubricated by the force feed system. An annular chamber 32 is formed in the piston from which numerous small holes 33 extend to the outside of the piston and deliver oil between the packing rings 34. A pipe 35 connecting with the annular chamber is arranged to slide with each movement of the piston, into and out of an oil receptacle 36 attached to the engine frame 1. If preferred a flexible tube may be substituted for the rigid pipe. A second opening 32^a leads from the annular chamber 32 normally closed by a plug 32^b but which is removed when the chamber is cleaned.

The operation of the engine will be readily understood from the foregoing description and a detailed recital thereof will not be necessary.

Among the advantages obtained by an engine constructed as above it may be noted that the speed may be varied gradually and a constant power be maintained at all speeds which is not possible with internal combustion engines connected directly with the

crank shaft, as they develop their maximum power at one speed only; hence, where speed and load of driven machine varies, a complicated change speed gear is used, and even with this a perfect control is not possible as to the maximum or highest efficient power can be developed only at as many speeds as there are changes of gear ratios. The parts of this engine which require attention are much more accessible than in engines at present in use. Lubrication is applied directly to the required parts instead of covering the whole machine with oil as in the splash system. This gives a cleaner engine and makes possible such adjustments as are required, especially when used on automobiles, without soiling the hands and clothing.

Having described the invention what is claimed is:

1. In an internal combustion engine, a crank shaft, a piston, a rock arm or lever between the crank shaft and the piston, a rack on the rock arm or lever, a movable fulcrum for the rock arm or lever adjustable in a plane at an angle to the length of the rock arm or lever when the latter is in the median position, and adjusting means for the fulcrum locking the latter to the rock arm or lever against displacement from adjusted positions, comprising a pinion carried by the fulcrum in engagement with the rack on the rock arm, a shaft carrying the pinion, another pinion on the shaft, a rack on a fixed portion of the engine engaged by the last named pinion, and means for rotating the shaft carrying the pinions.

2. In an internal combustion engine, a power cylinder, a piston, a crank shaft, a slotted rock arm or lever between said piston and crank shaft, a rack carried by the rock arm or lever, an adjustable fulcrum slidable in said rock arm or lever, a shaft carrying the sliding fulcrum, a rack carried by a fixed portion of the structure, a pinion on the fulcrum shaft engaging said fixed rack, means for rotating said fulcrum shaft, another pinion on the fulcrum shaft and engaging the rack on the rock arm or lever.

3. In an internal combustion engine, a power cylinder, a piston therein, a crank shaft, a rock arm or lever between said piston and the crank shaft, an adjustable fulcrum shaft for said rock arm or lever, a rack carried by a fixed portion of the engine, a rack on said rock arm or lever, pinions on said fulcrum shaft engaging both racks and means for rotating said fulcrum shaft.

4. An internal combustion engine comprising a plurality of explosion cylinders and pistons therein, a crank shaft, rock arms or levers between the crank shaft and pistons, an adjustable fulcrum shaft for said rock arms or levers and means for simultaneously changing the pivotal point of all the rock arms or levers.

5. An internal combustion engine comprising a plurality of power cylinders, pistons therein, a crank shaft, a slotted rock arm or lever between each of said pistons and the
5 crank shaft, a fulcrum shaft extending through the slots in all of the rock arms or levers, a rack bar on each rock arm or lever, a rack bar on a fixed portion of the engine, said last named rack bar being inclined to the rock lever when the latter is in a median position, pinions on said fulcrum shaft and engaging the
10 rack bars on the rock arms or levers and on a fixed portion of the engine, and means for rotating said fulcrum shaft to simultaneously change the pivotal points of all the rock arms or levers.
15 6. An internal combustion engine comprising a plurality of power cylinders, pistons therein, a crank shaft, a slotted rock arm or lever between each of said pistons and the crank shaft, a fulcrum shaft extending through the slots in all of the rock arms or levers, a rack bar on each rock arm or lever, a rack bar on a fixed portion of the engine, said last named rack bar being inclined to the rock lever when the latter is in a median position, pinions on said fulcrum shaft and engaging the
20 rack bars in the rock arms or levers and on a fixed portion of the engine, and means for rotating said fulcrum shaft to simultaneously change the pivotal points of all the rock arms or levers.
